UNITED STATES PATENT OFFICE

2,498,901

PAPER FASTENER

Samuel Segal, New York, N. Y., assignor to
 Wilson-Jones Company, Chicago, Ill., a corporation of Massachusetts,

Application September 18, 1944, Serial No. 554,568

5 Claims. (Cl. 24—153)

1

This invention relates to a fastener of the type ordinarily used to secure a plurality of sheets of paper or similar material together temporarily. It is an object of this invention to provide improved means for facilitating the securing of a compressor plate to the prongs of a base member. It is a further object of this invention to provide a compressor plate with means for speeding up filing operations by decreasing the time required for manipulating the fastener. Other objects of this invention will become apparent upon reading the following description, taken in conjunction with the accompanying drawings, in which:

Figure 1 is a perspective view of one embodiment of my improved fastener secured to a stack of sheets;

Figure 2 is a longitudinal sectional view taken along the lines II—II of Figure 1;

Figure 3 is a cross sectional view taken along the line III—III of Figure 2;

Figure 4 is a perspective view showing the prongs of the base member projecting through a stack of sheets and the compressor plate in position to engage the prongs;

Figure 5 is a detail perspective view of one of the sliding keepers;

Figure 6 is a detail perspective view of the compressor plate;

Figure 7 is a view, similar to Figure 1, showing another embodiment of my improved fastener;

Figure 8 is a longitudinal sectional view taken along the line VIII—VIII of Figure 7;

Figure 9 is a cross sectional view taken along the line IX—IX of Figure 7;

Figure 10 is a view, similar to Figure 1, showing another embodiment of my improved fastener;

Figure 11 is a view, similar to Figure 1, showing another embodiment of my improved fastener;

Figure 12 is a cross sectional view taken along the line XII—XII of Figure 11;

Figure 13 is a view, similar to Figure 1, showing another embodiment of my improved fastener;

Figure 14 is a cross sectional view taken along the line XIV—XIV of Figure 13; and

Figure 15 is a detail perspective view of another embodiment of my compressor plate.

Referring to Figures 1 to 6 of the drawings, the reference numeral 2 indicates a base member having a pair of prongs 3 extending from opposite ends. The prongs may be integral with the base member, as illustrated, or they may be secured to the base member in any suitable fashion. A

2

plurality of sheets 4 of paper or similar material, provided with a pair of apertures 5, is impaled on the prongs 3. A compressor plate 6, adapted to engage the prongs 3, is positioned on top of the sheets 4 between the prongs 3.

The compressor plate 6 comprises a channel-like member 7 having upstanding walls 8 and side flanges 9. The channel member 7 rests on the stack of sheets 4 and the flanges 9 are spaced from the surface of the sheets sufficiently to permit free sliding movement of a pair of keepers 10. An embossment 11 is provided adjacent each end of the channel 7 for a purpose hereinafter described.

The sliding keeper 10 comprises a channel member 12 adapted to fit inside the channel 7 and is provided with a pair of side flanges 13 adapted to fit over the flanges 6. The flanges 13 are bent downwardly and inwardly, as indicated at 14, to embrace the flange 6. The relationship between the keeper 12 and the channel member 7 is such that the keeper may slide longitudinally of the compressor plate with a relatively small amount of friction. One flange 13 is provided with a finger 15 extending transversely across the channel 12. The finger 15 may be bowed slightly, as indicated at 16, to provide rigidity.

The channel member 12 is provided with a notch 17 in its end that is closest to the finger 15. When the sliding keepers 10 are assembled on the compressor plate, as indicated in Figure 4, the embossment 11 engages the notch 17 to prevent the keepers from being moved longitudinally off the compressor plate. When the keepers are in their outermost positions, as indicated in Figure 4, the fingers 15 are just beyond the outer extremities of the compressor plate so that they may act as guides in positioning the compressor plate relative to the sheet retaining prongs 3.

From the position indicated in Figure 4, the compressor plate is moved forwardly so that the prongs are engaged between the fingers 15 and the outer edge of the channel members 12 and 7. The prongs are then bent inwardly over the channel members 12 and 7 and the sliding keepers are moved inwardly toward the center of the compressor plate. If desired, the compressor plate may be furnished with an embossment 18, similar to the embossment 11, at its medial position so as to prevent the sliding keepers from moving beyond the medial position. As illustrated in Figure 1, the fingers 15 project over the prongs 3 to retain them in the channel 7 so as to securely maintain the plurality of sheets 4 in securely bound relationship.

When it is desired to add or remove any sheets from the stack of sheets 4 it is necessary only to move the sliding keepers 10 outwardly, to bend the prongs 3 upright, and remove the compressor plate by a simple transverse movement. With a conventional paper fastener, if the prongs are overlapped, or if they are close together at their ends, it is necessary to slide one keeper in one direction to free its prong and then to slide it back in the opposite direction before the other keeper may be slid to free its prong. The same time consuming steps are necessary in order to secure the compressor plate to the prongs in a conventional fastener.

The embodiment illustrated in Figures 7, 8 and 9 is substantially similar to the embodiment previously described, the only differences being that the prongs 3' are each provided with an aperture 19 disposed near the free end, and the finger 15' is provided with an embossment 20. The embossment 20 makes the finger 15' sufficiently rigid so that it is not necessary to bow the finger as in the previously described embodiment. When the keeper 10' is slid over the compressor plate with the finger 15' overlying the prong 3' the embossment 20 will engage the aperture 19 to maintain the keeper and prong in interlocking engagement against accidental displacement. It is obvious that a slight positive pressure will be sufficient to force the sliding keeper from this position.

The embodiment illustrated in Figure 10 is similar to that shown in Figures 7, 8 and 9 except that the sheet retaining prongs 3'' are provided with longitudinal slots 21 instead of the apertures 19.

The embodiment illustrated in Figures 11 and 12 is substantially similar to that shown in Figure 10 except that the sliding keeper 10'' is folded to provide an upstanding projection 22. In this embodiment the finger 15'' does not require any embossment because the projection 22 fits into the slot 21 to serve the same purpose. The projection 22 may be sufficiently high to form a positive stop against the end of the slot 21 so that it may be impossible to slide the keeper 10'' past the free end of the sheet retaining prongs 3''.

In the embodiment illustrated in Figures 13 and 14 the base member is the same as illustrated in Figures 1 to 6. The compressor plate 23 comprises a channel member 24 having longitudinal flanges 25 and 26. A pair of sliding keepers 27 is mounted on the flanges 25 and 26. The flanges 25 and 26 are upset adjacent the outer ends of the compressor plate, as indicated at 28 and 29 to restrict the sliding movement of the keepers 27. The flange 25 is provided with extensions 30 projecting beyond the ends of the channel member 24. The extensions 30 facilitate assembly of the compressor plate with the sheet retaining prongs by lining the compressor plate up with the prongs horizontally. When the prongs 3 are standing upright it is necessary only to push the compressor plate transversely of the prongs until the extensions 30 engage the edges of the prongs. The prongs are then bent downwardly and the sliding keepers are moved over them to securely retain the papers in the stack 4 in bound relationship.

The embodiment illustrated in Figure 15 is substantially similar to that described in Figures 13 and 14 except that the extensions 30' are formed on the sliding keepers 27' instead of on the flanges of the compressor plate. In this

embodiment a stop member 31 is provided at each end of the flange 26'. In assembling this compressor plate with the base member the sliding keepers 27' should be moved to their outermost position so that the extensions 30' will serve as guide members to line the compressor plate up with the sheet retaining prongs.

Although I have described several embodiments of my invention in detail, it will be understood that the description thereof is illustrative, rather than restrictive, as many details may be modified or changed without departing from the spirit or scope of my invention. Accordingly, I do not desire to be restricted to the exact details of construction described, except as limited by the appended claims.

I claim:

1. In a fastener, a base member having a prong projecting therefrom, a compressor plate, said prong being positioned over said compressor plate, and a keeper having a portion slidable between said compressor plate and said prong, said keeper having a finger projecting over said prong.

2. In a fastener, a base member having a pair of sheet retaining prongs projecting therefrom, said sheet retaining prongs each having a longitudinally extending recess stopping short of its free end, a compressor plate positioned under said sheet retaining prongs, and a pair of sliding keepers each having a portion projecting into the recess of one of said sheet retaining prongs to limit the sliding movement of said keepers towards the free ends of said sheet retaining prongs.

3. In a fastener, a compressor plate, a base member having a sheet retaining prong bent over said compressor plate, a keeper slidable on said compressor plate with a part of said keeper under and another part over said sheet retaining prong, and cooperating means on said keeper and said sheet retaining prong limiting the sliding movement of said keeper in one direction.

4. In a fastener, a compressor plate, a base member having a sheet retaining prong bent over said compressor plate, and a keeper slidable on said compressor plate with a part over and a part under said sheet retaining prong, said keeper and said sheet retaining prong having interengaging parts for maintaining said keeper in engagement with said sheet retaining prong.

5. In a fastener, a compressor plate having a longitudinally extending channel provided with a horizontal flange on each lateral edge, a keeper slidable over said flanges, a finger integral with said keeper, said finger extending transversely of said channel, an upstanding embossment in said channel, and a notch in said keeper engaging said embossment to limit the outward movement of said keeper relative to said compressor plate, said finger being spaced entirely beyond the end of said compressor plate when said keeper is in its outermost position.

SAMUEL SEGAL.
